(57) **CLAIM**

The ornamental design for an automobile, as shown and described.

DESCRIPTION

1. Automobile

2. Automobile

FIG. 1.1 is a front right side perspective view of an automobile according to a first embodiment of the present design;

FIG. 1.2 is a rear left side perspective view of an automobile according to a first embodiment of the present design;

FIG. 1.3 is a front view thereof;

FIG. 1.4 is a rear view thereof;

FIG. 1.5 is a left side view thereof;

FIG. 1.6 is a right side view thereof;

FIG. 1.7 is a top view thereof;

FIG. 2.1 is a front right side perspective view of an automobile according to a second embodiment of the present design;

FIG. 2.2 is a rear left side perspective view of an automobile according to a second embodiment of the present design;

FIG. 2.3 is a front view thereof;

FIG. 2.4 is a rear view thereof;

FIG. 2.5 is a left side view thereof;

FIG. 2.6 is a right side view thereof; and

FIG. 2.7 is a top view thereof.

The bottom view of the automobile according to each of the first and second embodiments of the present design is omitted since the bottom of the automobile is invisible in use.
